DESIGN FOR A PAIR OF SPECTACLES

Albert George McNeill, Philadelphia, Pa., assignor
to Bachmann Bros., Inc., Philadelphia, Pa., a
corporation of Pennsylvania

Application September 16, 1947, Serial No. 141,432

Term of patent 14 years

(Cl. D57—1)

To all whom it may concern:

Be it known that I, Albert George McNeill, a citizen of the United States, residing at Philadelphia, in the county of Philadelphia and Commonwealth of Pennsylvania, have invented a new, original, and ornamental Design for a Pair of Spectacles, of which the following is a specification, reference being had to the accompanying drawing forming part thereof wherein:

Figure 1 is an elevational view of a pair of spectacles, showing my new design;

Fig. 2 is a sectional view, partly in elevation, taken on the line and as viewed in the direction of the arrows 2—2 of Fig. 1; and

Fig. 3 is a plan view thereof.

I claim:

The ornamental design for a pair of spectacles, as shown.

ALBERT GEORGE MCNEILL.
